LADY'S SLIP

Rosaria D'Amato, New York, N. Y.

Application October 23, 1935, Serial No. 46,359

1 Claim. (Cl. 2—73)

This invention relates to ladies' garments and particularly to what is known as a slip commonly worn between the undergarments and dress of the wearer.

5 The object of this invention is to provide a slip comprising main front and back panels, the upper portions of which are joined by small inclined side panels all cut in a perfect bias silhouette, there being arranged between each side panel and 10 the back panel a strip of "lastex" material; the design of the panels and the "lastex" strips being such that there is eliminated in the forming of the slip the usual bust and back piece seaming as well as the strain and breakage incident thereto.

15 Another object of the invention resides in the placing of the seams on each side of the slip, the constructional arrangement of the panels comprising the same being such that the slip acts to slenderize the form and at the same time will 20 not pull up when the wearer is sitting.

Other objects of the invention relate to the provision of a slip that will be durable; that will obviate strain on the seams; that will be perfect form fitting; that will not bulk or ride up on the 25 body of the wearer thus adapting itself to the grace and carriage of the body during all movements thereof; that will consist of a minimum of parts and that will be simple to manufacture.

The above and still other objects of the invention will become apparent as the description thereof given hereunder proceeds with reference to the accompanying drawing wherein:—

Figure 1 is a back elevational view of the slip, Figure 2 is a front elevational view thereof, and

35 Figure 3 is a side elevational view thereof.

Referring to the accompanying drawing by numerals 10 indicates the body of the slip and 11 the bust portion thereof. The body 10 is made up of a front panel 12 and a rear panel 13 so cut that 40 the threads thereof will be on a bias in the manner well known whereby when placed on the body in the completed slip, the same will drape itself thereon as to produce a perfect form fit.

The front panel 12 is so patterned that the 45 upper portion thereof is provided with symmetri- cally disposed outwardly and upwardly inclined bust portions 14 which with the main portion of the front panel 12 define at the sides of said panel and beneath said bust portions substantially tri- 50 angular cut-away portions each indicated by the letters a—b—c, for a purpose to be hereinafter described. The back panel 13 is of less length than the front panel 12, the body portions of both, however, being substantially identical; the upper 55 portion of the back panel 13 having symmetrical

upwardly and inwardly inclined edges 15, with the point of juncture 16 at the medial longitudinal center line of the panel.

The front panel 12 and back panel 13 are joined along their side edges to form the seam 18, which viewing Figure 3 is shown to be at the side of the slip 10 and as extending lengthwise thereof, it being understood that there is a similar seam 18 at the other side of the slip (not shown). The bottom edge of the joined front and back panels is 10 provided with the conventional finished seam on hem 19.

To complete the slip there are provided two 15 side panels 20 each of identical shape. Each side panel 20 is patterned substantially in the form of a rectangle and is preferably straight cut, that is, with the threads at right angles to the edges, in contradistinction to the bias cut of the front and back panels 12 and 13. The side panels 20 are of 20 a width less than the length of the cut-away portion b—c, viewing Figure 3 and are joined to the front panel 12 along the seams 21 and 22. Prior to the joining of the side panels 20 to the front panel 12, the same is pleated as at 23 to 25 render the bust portion 11 form fitting.

In the space between the side panels 20 and the inclined edges 15 of the back panel 13 are disposed strips of "lastex" material 25, with the elastic threads therein disposed transversely of the length of said strips whereby the strips of "lastex" material 25 are stretchable in all directions but not lengthwise thereof. The "lastex" strips 25 are joined to the side panels 20 at the seam 26 and to the edge b—c of the front panel along the seam 22 and to the edge 15 of the back panel 35 along the seam 27.

The formation of the side panels 20 are such that the edges 28 thereof opposite the seams 22 are at the back of the slip, being inclined down- 40 wardly and inwardly, and with the coextensive edge 29 of the "lastex" material 25 meet at the juncture 16, see Figure 1. The top edge of the slip 10 is preferably provided with a fanciful binding strip 30 to provide a finished appearance.

45 As illustrated in the drawing, there are provided shoulder straps 31 which are connected to the slip 10 at the highest points on the front and back panels 12 and 13 as shown.

From the construction and manner of joining the parts that go to make up the slip, it will 50 be apparent that a perfect fitting slip will have been provided, particularly in view of the bias cut of the front and rear panels. In addition, the particular placing of the "lastex" strips will 55

act to render the slip particularly adaptable to all body movements of the wearer without placing the seams under any strain, thus adding to the durability of the slip.

5 It will thus be noted that the front and rear panels are tapered and that the bust portions of the front extend from the tapered portions in the form of a flat V.

Having thus set forth and disclosed the nature
10 of this invention, what is claimed is:

A form fitting slip comprising front and rear panels each made of bias cut material; the front panel at the lower region of the bust being tapered; upwardly and outwardly inclined bust
15 portions formed as a part of said front panel extending from the tapered portion thereof in the form of a flat V, the rear panel having a body portion similar to that of the front panel and tapered at its upper end to form inclined edges
20 intersecting at a point located substantially be-

neath the V-shaped neck defined by the bust portions of the front panel; said front and rear panels being joined together at their side edges; and a pair of substantially rectangular side panels formed of straight cut material fitted to the front and rear panels; a strip of "lastex" material connecting the lower longitudinal edges of the side panels with inclined edges of the rear panel, a portion of the upper longitudinal edges and the lower transverse edges of said side panels being 10 respectively joined to the inside edges of the bust portions and the edges defined by the tapered portion of said front panel, the other transverse edges of said side panels being free and unattached and inclined with reference to each other; and shoulder straps connected at their front ends to the uppermost corners of the bust portions and at their rear ends to the free corners of said side panels.
